UNITED STATES PATENT OFFICE.

JAMES WALLACE RUNNER, OF SHELBY, MICHIGAN.

ATTACHMENT FOR CUFFS AND CUFF-BUTTONS.

SPECIFICATION forming part of Letters Patent No. 684,724, dated October 15, 1901.

Application filed December 20, 1900. Serial No. 40,532. (No model.)

To all whom it may concern:

Be it known that I, JAMES WALLACE RUNNER, a citizen of the United States, and a resident of Shelby, in the county of Oceana and State of Michigan, have invented a new and Improved Attachment for Cuffs and Cuff-Buttons, of which the following is a full, clear, and exact description.

The object of the invention is to provide a new and improved attachment for cuffs and cuff-buttons to prevent the cuff-buttons from rattling, especially when in use on celluloid or similar waterproof cuffs.

The invention consists of novel features and parts and combinations of the same, as will be fully described hereinafter and then pointed out in the claim.

A practical embodiment of the invention is represented in the accompanying drawings, forming a part of this specification, in which similar characters of reference indicate corresponding parts in all the views.

Figure 1 is a perspective view of the improvement as applied. Fig. 2 is a sectional plan view of the same. Fig. 3 is a side elevation of the improvement, and Fig. 4 is a transverse section of the same on the line 4-4 in Fig. 3.

The attachment consists, essentially, of a spring A, held on the shank B' of a cuff-button B and interposed between the inner head B² of the cuff-button and the inside of the cuff C, as is illustrated in Figs. 1 and 2. The spring A is so arranged that it exerts a pressure on the cuff-button in the direction of the length of the shank to prevent the cuff-button from rattling on the cuff.

As illustrated in the drawings, the spring A is preferably in the form of a U-shaped plate of spring material, such as celluloid or 40 the like, and is formed with registering slots A' for the passage of the shank B', the slots having reduced portions A² for the passage of the plate upon the shank, as will be readily understood by reference to Fig. 2. 45

The device is very simple and durable in construction, can be readily applied, and does not interfere in any way with the workings or appearance of the cuff-button B, which may be of any approved construction and 50 have a removable outer head or not, as desired.

Having thus fully described my invention, I claim as new and desire to secure by Letters Patent—

As a new article of manufacture, an attachment for cuffs and cuff-buttons adapted to be interposed between the inner head of a button and the cuff to prevent the button from rattling, the same consisting of a U- 60 shaped plate of spring material having each of its members provided with an opening having a reduced portion leading out through the edge of the member, the openings and the reduced portions thereof of the members 65 of the plate registering with each other, as set forth.

In testimony whereof I have signed my name to this specification in the presence of two subscribing witnesses.

JAMES WALLACE RUNNER.
